UNITED STATES PATENT OFFICE.

WILLIAM B. HAYDEN, OF NEW YORK, N. Y.

SPARKING PLUG.

No. 858,282.

Specification of Letters Patent.

Patented June 25, 1907.

Application filed February 6, 1907. Serial No. 356,027.

To all whom it may concern:

Be it known that I, WILLIAM B. HAYDEN, a citizen of the United States, residing at New York, in the county of New York and State of New York, have invented new and useful Improvements in Sparking Plugs, of which the following is a specification.

This invention relates to sparking plugs for explosive engines and the object thereof is to provide the plug with means arranged exteriorly of the cylinder of the engine and independent of the water jacket of the cylinder for cooling the working parts and insulations of the plug thereby preventing the heating of certain of the working parts of the plug to such an extent as to injure them which would interfere with the operation of the plug. In view of such arrangement the operation of the plug is not retarded and furthermore the life of the plug is prolonged.

A further object of the invention is to provide what may be termed a water jacketed sparking plug independent of the cylinder of the engine and which shall be simple in its construction, strong, durable, efficient in its use, readily positioned with respect to the cylinder of the engine, and comparatively inexpensive to manufacture.

With the foregoing and other objects in view, the invention consists in the novel construction, combination, and arrangement of parts hereinafter more specifically described and illustrated in the accompanying drawings, wherein is shown the preferred embodiment of the invention, but it is to be understood that changes, variations, and modifications can be resorted to which come within the scope of the claims hereunto appended.

In describing the invention in detail reference is had to the accompanying drawings, wherein like reference characters denote corresponding parts throughout the several views and in which

Figure 1 is a longitudinal sectional view of a sparking plug in accordance with this invention attached to the cylinder of an engine, the latter being broken away and shown in section, and Fig. 2 is a section on the line 2—2 Fig. 1.

Referring to the drawings by reference characters 3 denotes the outer section of the plug and 4 the inner section, the latter being hollow and provided with peripheral threads 5 adapted to engage in a screw-threaded opening 6 formed in the cylinder wall 7 so that the plug will be secured in position.

The cylinder has a water-space 7^a. The inner end of the section 4 is provided with a protuberance 8 carrying a contact point 9, the protuberance 8 and contact point 9 constituting a fixed electrode. At the outer end of the inner section 4 a laterally-extending annular offset 10 is provided, the latter having an annular flange 10^a. Said offset 10 is recessed on that face which opposes the cylinder 7 of the engine and secured to the section 4 and positioned against the recessed face of the offset 10 as well as overlapping said offset is a disk 12 which in connection with the recess 11 of the offset forms a water chamber. The disk 12 has formed integral therewith an inlet and an outlet nipple 13, 14, respectively, said nipples communicating with the water chamber. A water supply pipe 15 communicates with the nipple 13 and a discharge pipe 16 is connected to the nipple 14. A lock-nut 17 is mounted upon the section 4 for securing it in position when the plug is in engagement with the cylinder 7.

The section 3 of the plug is hollow and at its inner end is formed with an annular flange 18 which is secured by the holdfast devices 19 to one face of the offset 10. Journaled in the section 3 as well as projecting from one side thereof is a rock-shaft 19^a carrying an arm 20 which is connected to an armature 21 of an electro-magnet 22. The arm 20 carries a set-screw 23 having one end thereof bearing against a spring 24, the function of the latter being to shift the arm 20 so as to retain the armature 21 away from the magnet 22.

The reference character 25 denotes a vibratory arm which at one end is connected to the shaft 19^a within the section 3 and the said vibratory arm 25 extends through the section 4 as well as projecting from the inner end thereof, and said arm 25 carries a contact 26 which opposes the contact 9. The arm 25 and contact 26 form a vibratory electrode. The section 3 is insulated from the section 4, as at 27. Protuberances 28, 29 are provided for the binding posts 30, 31 to which are connected the leading-in wires. Branch wires 32, 33 lead from the binding posts to the magnet. A cover for inclosing the working parts of the plug carried by the section 3 is indicated by the reference character 34 and which is detachably connected to the flange 10^a of the offset 10.

From the foregoing arrangement of parts it will be evident that what may be termed a "water jacket" is provided for the plug

whereby the insulation between the two sections of the plug and the working parts carried by one of the sections is cooled and that the water jacket is entirely independent of 5 the water jacket of the cylinder of the engine; under such conditions the working parts of the plug are prevented from being overheated and the life of the plug is increased.

What I claim is:

- 10 1. An electrical sparking plug for explosive engines comprising an inner and an outer section, said inner section having a fixed electrode, a vibratory electrode coöperating with the fixed electrode, means carried by the 15 outer section of the plug for actuating the vibratory electrode, and means carried by the inner section of the plug and independent of the engine cylinder for cooling the actuating means for the vibratory electrode.
- 20 2. An electrical sparking plug comprising both terminals an inner section having a recessed offset, a plate secured to the offset and forming in connection with the recessed portion of the offset a water chamber, means for

establishing communication between the 25 water chamber and a source of supply, means for conducting the water from said chamber, an outer section carrying an electrically-operated device, and means for securing the outer section to the offset. 30

3. A sparking plug for explosive engines adapted to extend through the wall of the cylinder of the engine and provided with an electrically-operated device for actuating an electrode, said plug further comprising a 35 fixed electrode, a lock nut for the plug, and a water jacket surrounding a portion of the plug and independent of the water jacket of the cylinder of the engine for cooling said device. 40

In testimony whereof I have hereunto set my hand in presence of two subscribing witnesses.

WILLIAM B. HAYDEN
